UNITED STATES PATENT OFFICE.

EDWARD WILSON, OF ST. LOUIS, MISSOURI, ASSIGNOR TO WILSON ENGINEERING COMPANY, OF ST. LOUIS, MISSOURI, A CORPORATION OF MISSOURI.

ROTARY COMPRESSOR.

Application filed November 15, 1920, Serial No. 424,034. Renewed July 14, 1923.

To all whom it may concern:

Be it known that I, EDWARD WILSON, a citizen of the United States, residing at St. Louis, Missouri, have invented new and useful Improvements in Rotary Compressors, of which the following is a specification.

This invention relates to rotary compressors, and consists in the novel construction hereinafter disclosed.

10 An object of the invention is to provide a compressor having a continuously operating rotor composed of a cylinder and piston, with means whereby a relative oscillating movement between the piston and cylinder is effected resulting in the ingress, compression and egress of volumes of air or gas in the compression chambers.

Another object of the invention is to provide a rotary compressor of the class described, including effective means for accomplishing the oscillating motion between the cylinder and piston, with provision for mounting the moving parts so as to prevent undue vibration or wear on the parts.

25 Another object of the invention is to provide in an apparatus of the class described suitable means for the induction, egress and control of the air or gas passing to and from the compression chambers.

30 Another object of the invention is to provide in an apparatus of the class described an improved form of sealing heads for the cylinder, whereby the escape of pressure from the compression chambers is minimized.

35 Another object of the invention is to provide an apparatus of the class described, wherein the lateral stresses, due to the difference in pressure on the rotor bearings, are eliminated by balancing the pressure generated within the compression chambers.

40 Additional advantageous features of the construction will be apparent from the following detailed description thereof taken in connection with the accompanying drawings, in which—

45 Fig. 1 is a vertical section through the apparatus showing the main features of the construction.

50 Fig. 2 is a cross section through the apparatus taken substantially on the line 2—2 of Fig. 1.

55 Fig. 3 is another cross section through the apparatus taken substantially on the line 3—3 of Fig. 1.

Fig. 4 is a sectional view through a portion of the apparatus taken substantially on the line 4—4 of Fig. 2.

Fig. 5 is a fragmentary view of a part of the apparatus illustrating particularly a portion of the oscillating mechanism for imparting the relative movement between the piston and cylinder.

Fig. 6 is a fragmentary view of further details of this construction.

Fig. 7 is a sectional view showing the passages by which the compressed air passes from the compression chambers.

In the embodiment of the invention illustrated in the drawings the apparatus is shown as including a main central casting having a base 1 which supports an inner cylindrical housing 2 and an outer housing 3, there being a space between the walls of the housings 2 and 3 forming a chamber 4 for the reception of a fluid, thus providing a water jacket for cooling the apparatus.

A head member 5 is bolted to the central casting and is preferably formed with a tongue and groove joint, sealed by a gasket 6. The head member has a lateral extension comprising spaced walls 7 and 8 forming a chamber 9 therebetween for the reception of a cooling fluid. The end of the extension terminates in a circular flange 10 to which is bolted a head piece comprising an outer member 11 and an inner flange 12 joined together and formed integrally with arms 13, the flanges 10 and 12 being secured together by bolts.

The opposite end of the central casting supports a head piece 14 that is bolted directly to the central casting, the joint between the two preferably being a tongue and groove connection sealed by a gasket 15. Extending from the head piece 14 is a bell-shaped casting 16 that terminates in a cylindrical extremity 17 of less diameter. The bell-shaped casting 16 constitutes a housing for the mechanism for the oscillation of the cylinder and the piston, and the cylindrical extension constitutes a support for the bearings of a shaft as will be described hereinafter.

It will, of course, be understood that while the details of the housing have been specifically described, that it is not intended to indicate that the specific construction of the housing as shown is essential, but the housing may be formed in any convenient

cludes an intake pipe 54 in the left extension of the main housing (Fig. 1), this intake pipe registering with a lantern 55 mounted in the extension and encompassing the shaft 18. It will be noted that the space between the housing and the shaft on either side of the lantern is packed with packing material 56 and that a packing gland 57 is bolted to the end of the housing extension to accomplish the compression of the packing, thereby preventing the escape of pressure from either side of the lantern 55 which constitutes a separator in the opening of the extension of the housing. From the intake conduit 54 the air passes through slots in the lantern and into a conduit 58 formed by a cavity in the shaft 18 through openings 59 through the walls of the shaft located within the lantern 55. The cavity in the shaft 18 extends to a point within the piston sectors of the shaft through which there are slots 60 that communicate with transverse conduits 61 in the piston sectors. The ends of the conduits 61 discharge at the edge of the piston sectors and are controlled by outwardly opening disc valves 62 that communicate with conduits 63 leading into the compression chambers. The discharge conduits are formed in the sectors 26 of the cylinder and include similarly formed conduits 64 controlled by inwardly opening disc valves 65. The conduits 64 discharge into the space between the cylinder and the housing, there being a discharge passage 66 extending from this chamber between the cylinder and the main body of the housing.

From the foregoing the operation of the apparatus will be understood to be as follows: The air is drawn into the compression chambers from the inlet passage 54, through the passages as described, into the compression chambers within the cylinder. The shaft 18 is revolved at a constant speed and the cylinder through the crank connections is oscillated with respect to the piston sectors, so that on each rotation of the shaft the piston sectors will traverse the space between the sectors 26 carried by the cylinder, thus compressing the contents of the compression chambers, the compressed air or gas being forced out of the compression chambers at the end of the stroke into the chamber between the cylinder and the housing from whence it is discharged through the discharge passage 66. The length of the stroke of the piston is determined by the degree of eccentricity of the shafts 18 and 41. It will be noted that the entire apparatus is balanced as to pressure and that it is thoroughly sealed against loss of pressure at any point. It will, likewise, be noted that provision has been made to equalize the wear between the moving parts and particularly that the cylinder heads have an equalized

rotary and dragging motion, due to the pin-in-slot connection between them and the heads of the cylinder.

While I have illustrated and particularly described the apparatus as an air compressor it will, of course, be obvious that the same combination of parts may be utilized as a motor and that power may be developed by reversing the action from that described so as to develop power in place of compressing air or gas.

I am aware that numerous features of the construction may be changed without departure from the spirit and scope of the invention. I do not limit myself, therefore, to the exact construction shown and described, but what I claim and desire to secure by Letters Patent, is:—

1. In an apparatus of the class described, the combination with a housing, of a revoluble cylinder mounted within the housing, a piston mounted within the cylinder, a drive shaft, and mechanism for imparting an oscillating motion between the piston and the cylinder from a continuous rotation of the drive shaft.

2. In an apparatus of the class described, a housing, a revoluble cylinder mounted within the housing, said cylinder having internal sectors, a main shaft, piston sectors on the main shaft arranged to move within the chambers formed between the sectors on the cylinder, and mechanism intermediate the main shaft and the cylinder whereby an oscillating motion between the pistons and the cylinder is imparted from a continuous rotation of the main shaft.

3. In an apparatus of the class described, the combination with a housing, of a main shaft revolvably mounted in the housing, a cylinder revolvably mounted with respect to the main shaft, piston sectors carried by the main shaft, sector partition walls on the cylinder extending between the pistons, and mechanism driven by the main shaft for imparting an oscillating motion between the cylinder and pistons from a continuous rotation of the main shaft.

4. In an apparatus of the class described, the combination with a housing, of a main shaft, ball bearings for revolvably supporting the main shaft, a cylinder revolvably supported in ball bearings with respect to the main shaft, inwardly extending sectors on the cylinder constituting partitions forming compression chambers, pistons carried by the main shaft and arranged to operate within the compression chambers, and mechanism intermediate the main shaft and the cylinder whereby an oscillating motion is imparted to the cylinder with respect to the pistons from a continuous rotation of the main shaft.

5. In an apparatus of the class described, the combination with a housing, of a main

- shaft revolvably supported in the housing, piston sectors carried by the main shaft, a cylinder embracing the pistons and the main shaft having inwardly extending sector partitions constituting compression chambers in which the pistons operate, floating heads for the cylinder, connections between the floating heads and the cylinder whereby a relative rotary movement between the heads and cylinder is permitted, means for admitting and exhausting pressure from the compression chambers, and driving connections intermediate the main shaft and the cylinder whereby an oscillating motion is imparted to the cylinder with respect to the pistons from a continuous rotation of the main shaft.
6. In an apparatus of the class described, the combination with a housing, of a main shaft revolvably supported therein, piston sectors carried by the main shaft, an independently revolvable cylinder having inwardly extending sector partition walls extending intermediate the pistons, a crank arm carried by the main shaft, an eccentrically mounted disc in respect of the main shaft, link connections between the disc and the cylinder, and connections between the crank arm and said disc.
7. In an apparatus of the class described, a housing, a main shaft revolvably supported in the housing, oppositely disposed piston sectors carried by the main shaft, a cylinder independently movable with respect to the main shaft having sector partition walls extending between the pistons, a revolvable element connected with the cylinder, a revolvable member mounted to revolve on an axis eccentric with respect to the axis of the main shaft, an arm carried by the main shaft and pivotally connected with said revolvable member, and link connections between said revolvable member and the revolvable element connected with the pistons whereby an oscillating motion is imparted to the cylinder in respect of the pistons by continuous rotation of the main shaft.
8. In an apparatus of the class described, a revolvable cylinder, a main shaft, piston sectors carried by the main shaft, sectors carried by the cylinder intermediate the pistons, air conduit passages communicating with the space between the sectors on the cylinder, controlling valves in said passages, air conducting conduits in the sectors carried by the cylinder, said conduits communicating with the space exterior of the cylinder, and air controlling valves in said conduits.
9. In an apparatus of the class described, the combination with a housing, of a main shaft supported within the housing, a cylinder of less diameter than the housing revolvably supported in respect of the main shaft, inwardly extending sectors carried by the cylinder, pistons carried by the main shaft operating in the space between the sectors, inlet conduits communicating with the space between the sectors carried by the cylinder, conduits leading from said spaces to the space between the cylinder and the housing, and means for controlling the ingress and egress of the air to said space between the sectors carried by the cylinder.
10. In an apparatus of the class described, a main shaft, a cylinder revolvably supported with respect to the main shaft having segmental compression chambers formed therein, sectors carried by the main shaft and operating in said compression chambers, a housing spaced from the cylinder, air conduits leading from the exterior of the housing through the main shaft and discharging through the pistons to the compression chambers, conduits leading from the cylinder to the space intermediate the cylinder and the housing, and controlling valves whereby pressure is admitted and exhausted from the compression chambers.
11. In an apparatus of the class described, a rotor having compression chambers formed therein, a movable wall rotatably mounted in the rotor and operating in the compression chambers, a drive shaft, means for imparting an oscillating motion between the wall and the compression chambers by the continuous rotation of the drive shaft in one direction, and means for controlling the passage of air to and from said compression chambers.
12. In an apparatus of the class described, including a rotor, a compression chamber in the rotor having a relatively movable wall, a drive shaft and means for rotating the rotor and for imparting an oscillating motion to the wall during the rotation of the rotor by the continuous rotation of the drive shaft in one direction.
13. In a compressor, the combination of a housing, a shaft journaled for rotation in the housing, a cylinder within the housing, a piston within the cylinder on said shaft, and mechanism for imparting an oscillating motion to the cylinder by a continuous rotary movement of the shaft and piston.
14. A compressor, comprising a rotary shaft, a cylinder around the shaft, mechanism for imparting accelerated and retarded rotary movement to the cylinder by a continuous rotation of the shaft at uniform speed, and means operated by the shaft for effecting compression within the cylinder during such operation.
15. A compressor, comprising a rotary shaft, a cylinder around the shaft, mechanism for imparting accelerated and retarded rotary movement to the cylinder by a continuous rotation of the shaft at uniform speed, means operated by the shaft for effecting compression within the cylinder

during such operation, a housing enclosing the cylinder, and means for controlling the discharge of the compressed air or gas from the cylinder into the housing.

- 5 16. A compressor, comprising a housing, a shaft extending through the housing, a cylinder surrounding the shaft within the housing, compression pistons within the cylinder, and mechanism supported adjacent to the housing for imparting an accelerated and retarded rotary movement to the cylinder by continuous rotation of the shaft at uniform speed.
- 10 17. A compressor, comprising a housing, a shaft extending through the housing, a cylinder surrounding the shaft in the housing, pistons in connection with the shaft within the cylinder, an additional shaft mounted eccentrically relative to the first-named shaft, and mechanism in connection with said two shafts for imparting an accelerated and retarded rotary movement to said cylinder by the continuous rotation of said first-named shaft at uniform speed.
- 15 18. A compressor, comprising a housing, a shaft extending through the housing, a cylinder surrounding the shaft within the housing, means for admitting air into the cylinder through said shaft, pistons in connection with said shaft in said cylinder, and mechanism for imparting accelerated and retarded rotary movement to said cylinder by the continuous rotation of said shaft at uniform speed.
- 20 19. A compressor, comprising a housing, a shaft extending through the housing, a cylinder surrounding the shaft within the housing, floating end walls for said cylinder, means for supporting said end walls to close the ends of the cylinder and permitting lapping movements of said walls, pistons in connection with said shaft within said cylinder, and mechanism for imparting accelerated and retarded rotary movement to said cylinder by the continuous rotation of said shaft at uniform speed.
- 25 20. A compressor, comprising a housing, a shaft extending through the housing, a cylinder surrounding the shaft within the housing, floating end walls for said cylinder, means for supporting said end walls to close the ends of the cylinder and permitting lapping movements of said walls, pistons in connection with said shaft within said cylinder, an additional shaft, and mechanism controlled by said first-named shaft and said additional shaft for imparting accelerated and retarded rotary movement to said cylinder by the continuous rotation of said first-named shaft at uniform speed.

housing, means for admitting air into the cylinder through said shaft, pistons in connection with said shaft in said cylinder, a 40 shaft supported eccentrically with respect to said first-named shaft, and mechanism controlled by said two shafts for imparting accelerated and retarded rotary movement to said cylinder by the continuous rotation 45 of said first-named shaft at uniform speed.

20. A compressor, comprising a housing, a shaft extending through said housing, a cylinder surrounding the shaft within the housing, floating end walls for said cylinder, 50 means for supporting said end walls to close the ends of the cylinder and permitting lapping movements of said walls, pistons in connection with said shaft within said cylinder, and mechanism for imparting accelerated and retarded rotary movement to 55 said cylinder by the continuous rotation of said shaft at uniform speed.

21. A compressor, comprising a housing, a shaft extending through said housing, a cylinder surrounding the shaft within the housing, floating end walls for said cylinder, means for supporting said end walls to close the ends of the cylinder and permitting lapping movements of said walls, 60 pistons in connection with said shaft within said cylinder, an additional shaft, and mechanism controlled by said first-named shaft and said additional shaft for imparting accelerated and retarded rotary movement to 65 said cylinder by the continuous rotation of 70 said first-named shaft at uniform speed.

EDWARD WILSON.
